UNITED STATES PATENT OFFICE.

LOUIS H. WALES, OF NEW BRITAIN, CONNECTICUT, ASSIGNOR TO THE RUSSELL & ERWIN MANUFACTURING COMPANY, OF SAME PLACE.

DESIGN FOR A PADLOCK.

SPECIFICATION forming part of Design No. 32,619, dated May 1, 1900.

Application filed April 4, 1900. Serial No. 11,539. Term of patent 7 years.

To all whom it may concern:

Be it known that I, LOUIS H. WALES, a citizen of the United States, residing at New Britain, in the county of Hartford and State of Connecticut, have invented and produced a new and original Design for Padlocks, of which the following is a specification, reference being had to the accompanying drawings, forming part thereof.

Figure 1 is a perspective view of a padlock, showing my design. Fig. 2 is a rear elevation of the same.

As shown in the drawings, the contour in the main is a rectangular figure with a plane-surfaced shackle 3 projecting from the upper end. A little below the top of the case-body there is a projecting bar 4, extending across both the rear and the front sides, and a similar bar or projection 5 at both side edges connecting with the said bars 4. Above the bar

4, at the front, there are two narrow rectangular panels 6 7, the latter having a central knob-like ornament 8. At the ends of these panels is a small ornament 9. The body of the case below the bar 4, at both front and rear, is bordered at the top and bottom with the ledge 10 and at the sides with the double ledges 11. On the front there is a small rectangular figure 12, centrally arranged and with rounded ornaments 13 at each end, all forming a new and pleasing design, as shown.

Having described my invention, what I claim as new, and desire to secure by Letters Patent, is—

The design for a padlock, as herein shown and described.

LOUIS H. WALES.
